UNITED STATES PATENT OFFICE.

ROBERT RITCHIE SMITH, OF CHESTER, PENNSYLVANIA.

CRIB OR BED COVER.

1,426,230.

Specification of Letters Patent. Patented Aug. 15, 1922.

Application filed September 7, 1921. Serial No. 499,009.

To all whom it may concern:

Be it known that I, ROBERT RITCHIE SMITH, a citizen of the United States, residing at Chester, in the county of Delaware and State of Pennsylvania, have invented a new and useful Crib or Bed Cover, of which the following is a specification.

This invention has reference to crib or bed covers and its object is to provide a cover or blanket for application to a crib or bed, whereby an infant or young child may be amply protected, while in the crib, against exposure due to kicking or other movements resulting in dislodging the cover to an extent to expose the child to the effects of air or draughts, especially in cold weather, and which cover or blanket may also be used for adult invalids where exposure to air would be detrimental.

In accordance with the invention, the cover is formed of suitable sheets of materials such as is customarily used for the purpose. Stretched rubber or elastic strips are included between the sheets, running one way of the cover so that, when the child or other person is under the cover and the latter is made fast to fixed portions of the bed, the person, if restless, cannot kick off or otherwise disturb the cover to an extent to expose the child, the cover being elastic in one direction throughout substantially its entire area to maintain close contact with the child or other person at all times.

The invention will be best understood from a consideration of the following detailed description taken in connection with the accompanying drawings forming a part of this specification, with the understanding, however, that the invention is not confined to any strict conformity with the showing of the drawings, but may be changed and modified so long as such changes and modifications constitute no material departure from the salient features of the invention as expressed in the appended claims.

In the drawings:

Fig. 1 is a plan view, more or less diagrammatically illustrating an initial step in the manufacture of the cover or blanket.

Fig. 1^a is a plan view of a rubber strip such as is incorporated in the cover.

Fig. 2 is a section on the line 2-2 of Fig. 1 but drawn on a larger scale.

Fig. 3 is a plan view, more or less diagrammatically illustrating a further step in

the manufacture of the cover or blanket.

Fig. 4 is a cross-section similar to that of Fig. 2 but related to the showing of Fig. 3.

Fig. 5 is a plan view, showing the cover further progressed than in Figs. 1 and 3, and with certain portions separated or displayed.

Figs. 6, 7 and 8 are enlarged cross-sectional views of additional steps in the manufacture of the cover.

Fig. 9 is a plan view illustrating the final appearance of the completed cover.

Fig. 10 is a cross-section, more or less diagrammatically shown, of the cover applied ready to a bed or crib to receive the child.

Fig. 11 is a view similar to Fig. 10 but showing the cover or blanket stretched in opposition to the tendency of the rubber strips, as it would appear when covering a child or other person in the crib or bed.

Referring more particularly to Fig. 1, there are shown two sheets, 1 and 2, of cloth of such weave and color as the designer or manufacturer of the cover may choose. For convenience of handling, the fabric sheets 1 and 2 are made of appropriate size to permit considerable stretching and contraction in the covering area of the sheets, due to the manner of manufacture. While in no wise limiting the invention to any particular size, it has been found in practice that the fully spread or stretched sheets may approximate forty-eight inches in one direction by eighty inches in the other direction, but these dimensions may be departed from as expediency may dictate.

Combined with and located between the sheets 1 and 2 are rubber strips 3, which may be initially about forty inches long and about three inches wide and of appropriate thickness, but when these strips are stretched, their length is increased to about eighty inches and their width is reduced to about two inches for ordinary crib size, although these particular figures are not at all obligatory and may be increased for bed size.

The sheets 1 and 2 are each formed, in the direction of the length of the sheet, into spaced rows of tucks 4 formed by rows 6 of stitching, the tucks occurring on opposite faces of the sheets and the tucks being temporary and are later removed by pulling out the stitching 6. The tucks are so spaced as to occur about midway of the side edges of the rubber strips 3, after which other rows

7 of stitching are produced lengthwise of and parallel to the tucks and rubber strips, with the rows 7 of stitching traversing both the sheets 1 and 2 and the rubber strips 3, 5 on each side of the tucks and at or near the side edges of the rubber strips.

When the cover or blanket is initially formed the tucks 4 are present and the rubber strips 3 are stretched lengthwise and secured in place between the tucks of the sheets 1 and 2 by the rows 7 of the stitching, one strip between each pair of tucks, said sheets 1 and 2 being held by suitable frames, not shown. The rubber strips 3 are stretched to 15 the full length of the associated sheets, the rubber strips being stretched so that they are extended in length and reduced in width, as before stated, and are united at their long edges to the sheets 1 and 2 by the stitching 7. Now, while the sheets 1 and 2 are in a spread condition on the frame or other device, (not shown), for holding the sheets, and the rubber strips are in the stretched condition, the stitching 6 is removed from 25 the tucks to release them, and the stitching 7 is produced through the edges of the rubber strips uniting the sheets 1 and 2, whereupon the rubber strips, together with the sheets 1 and 2, are more or less drawn together or 30 shirred, for the width of the cover or blanket is reduced by the contraction of the previously stretched rubber strips, giving an appearance similar to the showing at 8 in Figures 8 and 9.

35 The cover is then finished by the application of marginal ruffles 9 or the like, while the cover is in the non-stretched or contracted condition, and also by the application on opposite side edges of the cover, 40 of tabs 10 designed to be fastened about the corner posts or other parts of a crib or bed. Furthermore, other tabs 11, which may be located midway of the cover, are provided for the purpose of enclosing the child in the 45 blanket, which latter is thus fastened about the child when it is desired to carry said child in the cover or blanket from one point to another.

In Figs. 9, 10 and 11 the cover is shown as 50 a whole at 12. Fig. 9 shows the blanket contracted or shirred by the contraction of the rubber strips. Fig. 10 shows the blanket fast to the crib or other piece of furniture, by which the child is supposed to be supported. Fig. 11 shows the extent to which 55 the blanket 12 may be stretched by the give of the rubber strips and because of kicking of the child without uncovering the child.

What is claimed is:—

60 1. A cover or blanket comprising facing and backing sheets of fabric with spaced, elastic strips located between the sheets and secured to the fabric, with the sheets shirred where secured to and by the elastic strips 65 to permit extension of the cover or blanket

in one direction and to hold the cover or blanket substantially non-extensible in a direction at right angles to the first named direction.

2. A cover or blanket comprising facing 70 and backing sheets of fabric with spaced elastic strips located between the sheets and secured at the edge portions thereto, with the sheets constructed to permit extension of the cover or blanket in one direction and 75 to hold the cover or blanket substantially non-extensible in a direction at right angles to the first named direction, said cover or blanket also having means along opposite edges for fastening the cover or blanket to 80 the sides of the crib or bed.

3. A cover or blanket comprising two sheets of fabric face to face and having substantially parallel spaced elastic strips confined between them and also made fast to 85 the fabric, with the sheets shirred and provided with tabs secured at intervals along opposite sides of the blanket for fastening said cover or blanket to the sides of the crib or bed, said cover or blanket also being provided with marginal ruffles exterior to the tabs and capable of participating in the extension movements of the cover or blanket.

4. A cover or blanket comprising facing 95 and backing sheets of substantially non-extensible material with interposed strips of rubber located between the sheets in spaced relation to each other and secured along their edges to the sheets, with the latter 100 shirred where so secured to permit the stretching of the rubber strips and the extension of the fabric sheets in one direction, said cover or blanket being substantially non-extensible in a direction at right 105 angles to the first named direction, and means for securing the blanket to a crib or bed, whereby a child or other person may have room for movement without danger of becoming uncovered.

5. A cover or blanket comprising sheets of fabric with substantially parallel elastic strips located between and secured at the edges to the fabric with the strips initially 110 stretched and then released to shir the joined sheets of fabric, finishing edge strips in the form of ruffles and capable of being stretched in the same direction as the elastic strips, and tabs at the marginal side 115 portions of the cover or blanket for fastening the latter to the sides of the piece of furniture and constituting holding means for the cover or blanket.

6. The method of forming extensible and contractible covers or blankets consisting in 120 providing like sheets of fabric, forming said sheets with temporary, spaced, tucks, holding the sheets in taut condition lengthwise of the tucks, introducing strips of elastic material between the sheets with the elastic 125 130

material stretched lengthwise, stitching the strips of elastic material and the sheets of fabric together on opposite sides of the tucks and then removing the stitching forming the tucks and releasing the stretch of the elastic material to permit said elastic material to contract the length of the sheets where joined by the elastic material, whereby to produce uniform shirring of said material.

7. The method of forming extensible and contractible covers or blankets consisting in providing like sheets of fabric, forming said sheets with temporary, spaced, parallel tucks, the tucks of one sheet matching those of the other, holding the sheets in taut condition lengthwise of the tucks, introducing strips of elastic material between the sheets with the elastic material stretched length-

wise, stitching the strips of elastic material and the sheets of fabric together on opposite sides of the tucks and then removing the stitching forming the tucks and releasing the stretch of the elastic material to permit said elastic material to contract the length of the sheets where joined by the elastic material, whereby to produce uniform shirring of said material, and then completing the cover or blanket by adding non-extensible ruffles cross-wise of the blanket along the edges of the latter after the release of the elastic bands, with the edges of the blanket participating in the shirring action of the body of the blanket.

In testimony that I claim the foregoing as my own, I have hereto affixed my signature.

ROBERT RITCHIE SMITH.
